(57) **CLAIM**

The ornamental design for a powder particle supply feeder, as shown and described.

DESCRIPTION

FIG. 1 is a front view of a powder particle supply feeder showing the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top front right perspective view thereof in a usage state;

FIG. 8 is a front view thereof in the usage state;

FIG. 9 is a left side view of the powder particle supply feeder with an input port shown in an open position; and,

FIG. 10 is a right side view of the powder particle supply feeder in the usage state.

The broken lines show portions of a powder particle supply feeder that form no part of the claimed design.
